ATTORNEY.

UNITED STATES PATENT OFFICE

RALPH T. SALSBURY, OF OAKLAND, CALIFORNIA

BOTTLE CAPPER

Application filed April 29, 1930. Serial No. 448,225.

This invention relates to improvements in bottle cappers and more particularly to machines for crimping crown caps on bottle necks.

5 Among the objects of the invention is to provide a simple, sturdy and effective capper.

Another object is to provide a capper easily adjustable to various sizes of bottles.

10 A further object is to provide a uniform capping stroke and application of power regardless of the height of the bottle. Other objects will appear as the description progresses.

15 In this specification and the accompanying drawings, the invention is disclosed in its preferred form. But it is to be understood that it is not limited to this form because it may be embodied in other forms.

20 It is also to be understood that in and by the claims following the description it is so desired to cover the invention in whatsoever form it may be embodied.

In the one sheet of drawings:

25 Fig. 1 is a side elevation of a bottle capper constructed in accordance with this invention.

Fig. 2 is an enlarged detail of the rack and pinion mechanism partly in vertical section on the line II—II, Fig. 1.

30 Fig. 3 is a similar view of the same taken on the line III—III, Fig. 2.

In detail the construction illustrated in the drawings, referring to Fig. 1, comprises 35 the base 1, having the upright standard 2 fixed therein. This base is adapted to be fastened to a bench, if required, and is preferably supplied with a resilient rubber pad 3 upon which the bottle X sits.

40 The upper portion of the standard 2 has the rack teeth 4 milled transversely therein, from below the head 5 downward a sufficient distance to accommodate the smaller sizes of bottles. This standard may be a length of

45 "cold rolled" rod.

The capping unit comprises a traveler A, preferably an integral casting, having the annular guides 6, 7 encircling the standard 2. This traveler has the transverse hubs 8, 9, see Fig. 2. The hub 9 is bored to receive

the diameter of the shaft 10, of the pinion 11 milled into the body thereof. The diameter of the shaft is turned down to form the stem 12 fitting the bore in the hub 8, against which the end of the pinion 11 abuts. 55

The stem 12 has a transverse hole therein, adjacent its rounded end 13, to receive the bent end 14 of the expansion spring 15 encircling the stem 12. The opposite bent end 16 of this spring engages a socket hole 60 in the hub 8 at 16.

This spring 15 performs the dual function of expansion to keep the pinion 11 laterally seated against the hub 8, and the additional function of torsion to restore the pinion to the inoperative position, after it has been rotated by means of the operating lever 17 extending through the head 10, and provided with the comfortable handle 17'.

The torsion of the spring 15 holds the lever 17 normally against the pin 18 projecting from the side of the traveler. The opposite end 17" of the lever protruding through the head 10 is adapted to stop against the pin 18 to prevent undue strain on the spring 15, 75 such as would unseat either of its ends 14, 16 from their respective sockets.

The pinion 11 is held in mesh with the rack teeth 4 by the expansion of the spring 15. Raising and lowering the lever 17 rotates the 80 pinion to raise and lower the traveler on the standard.

The operating lever of the traveler is readily adjustable by grasping the traveler in the left hand with the end 13 of the stem against 85 the palm. A slight pressure inward overcomes the tension of the spring 15, disengages the pinion from the rack, permitting the traveler to be raised and lowered at will, with respect to the height of the bottle 90 X. When the pressure is released the spring 15 snaps the pinion 11 back into mesh with the rack 4 at the selected level. The pin 18 should be long enough to retain the lever 17 95 in upright position during the lateral shifting of the pinion to disengage it from the rack.

The crimping ferrule 19 is screwed onto the threaded stud 20 fixed in the traveler. 100 The edge of this ferrule is flanged outwardly

to engage the fluted edge X' of the crown cap X'' , to compress the cap about the bead forming the mouth of the bottle, in the conventional manner.

5. If the teeth in the rack 4 and the pinion 11 are closely fitted and the straps 6, 7 snugly engage the standard 4, no further guiding of the traveler A is required. If, however, the workmanship is inferior, it may be desirable to mill the slot 21 in the back of the standard to guide the stud 22 fixed in the strap 6, to prevent lateral play of the traveler A on the standard.

15. The machine operates substantially as follows: The filled bottle X is placed upon the pad 3, the traveler A is lowered until the lower edge of the ferrule clears the cap X'' resting upon the top of the bottle. The handle 18 is then pulled down, which causes the pinion 11 to travel down the rack 4 and compress the edge X' of the cap within the ferrule, as described. When the handle 18 is released, the spring 15 restores it to the position shown in dotted lines, Fig. 1, leaving both hands of the operator free to handle the bottles and repeat the operation.

Having thus described this invention, what I claim and desire to secure by Letters Patent is:

30. 1. A bottle capper comprising a base; a standard fixed to said base and having a toothed rack thereon; a traveler guided on said standard; a transverse shaft protruding through said traveler and having integral pinion teeth engaging said rack; means for rotating said shaft; a torsion spring engaging said shaft and traveler and expanding between said traveler and the end of said shaft.
40. 2. A bottle capper comprising a base; a standard fixed to said base and having a toothed rack thereon; a traveler guided on said standard; a transverse shaft protruding through said traveler; a pinion on said shaft engaging said rack; a lever fixed in one end of said shaft, and a spring encircling said shaft having its opposite ends engaging said shaft and traveler respectively.
45. 3. A bottle capper comprising a standard having rack teeth therein; a traveler guided on said standard and having capping means thereon; a transverse shaft protruding through said traveler and having pinion teeth engaging said rack teeth; a lever on said shaft; a stop on said traveler engaging said lever; a torsion spring engaging said shaft and traveler and expanding between said traveler and the end of said shaft.
50. 4. A bottle capper comprising a round standard having rack teeth therein; a traveler encircling said standard and having capping means thereon; a transverse shaft having a reduced stem and protruding through said traveler and having pinion teeth engaging said rack teeth; a stop pin

projecting from said traveler; a lever extending through said shaft and adapted to engage both sides of said stop pin respectively; a torsion spring encircling said stem and having its ends engaging said stem and traveler respectively and expanding between said traveler and the end of said stem.

5. A bottle capper comprising a round standard having rack teeth therein and a longitudinal slot therein; a traveler encircling said standard and having capping means thereon; a transverse shaft having a said traveler; a lever extending through said traveler and having pinion teeth engaging said rack teeth; a stop pin projecting from said traveler; a lever extending through said shaft and adapted to engage both sides of said stop pin respectively; a torsion spring encircling said stem and having its ends engaging said stem and traveler respectively and expanding between said traveler and the end of said stem, and a stud on said traveler engaging said slot in the standard.

In testimony whereof I have hereunto set my hand this 24th day of April, 1930.

RALPH T. SALSBURY.
